APPARATUS FOR SELECTIVELY ACCUMULATING NOILS, SHORT FIBERS, OR OTHER MATERIAL, FROM A PLURALITY OF STATIONS

Ernest Clark, Abington, Mass., assignor to Abington Textile Machinery Works, Abington, Mass., a trust of Massachusetts

Application November 23, 1949, Serial No. 129,144

5 Claims. (Cl. 302—12)

1

This invention relates to an apparatus where material is transferred by suction from a given point or station to, and accumulated in, a receiver having air-exhausting means connected therewith.

The invention is more particularly concerned with the transfer of noils and short fibres from combing means to such a receiver, but in its broader aspect may be employed for the transfer of other materials.

The object of the invention is to enable the noils and short fibres, or other material, collected at a plurality of stations, such as at the discharge from a plurality of combing means, to be selectively transferred to a corresponding plurality of receivers in a predetermined sequence, so that the noils, short fibres, or other material, at each station will be accumulated in the corresponding receiver, and thus maintain segregated each type or character of noils, fibre, or other material in the respective receivers.

A further object of the invention is to provide such an apparatus in which a rotary valve mechanism is included in conduits leading from the respective receivers to the corresponding stations and in which the rotary valve of the said mechanism when rotated acts to establish communication in a predetermined sequence between the respective receivers and the corresponding stations.

A further object of the invention is to enable the noils and short fibres discharged from combing machines, such as either wool or cotton combers, to be selectively accumulated in a corresponding set of receivers, thus maintaining segregated the fibre from each one of a plurality of combing machines, or each group of a plurality of groups of combing machines.

The invention effects a great saving of time and labor where a number of combing machines are in operation not only in removing the material discharged from the combing machines, but in maintaining each type or character of such material segregated and readily available for later processing or for packaging. The invention enables the saving of time and labor to be effected in a highly efficient and economical manner and by the use of a minimum amount of power.

These and other objects and features of the invention will appear more fully from the accompanying description and drawings and will be particularly pointed out in the claims.

The drawings represent a preferred form of the invention as embodied in an apparatus for transferring to the receivers the noils and short fibres

2

discharged from a plurality of combing means, in this case a plurality of groups of combing machines such as the well-known Noble combers.

Figs. 1 and 2 are a plan view of an apparatus embodying the invention, chiefly in diagrammatic form, and with the portion shown in Fig. 2 being a continuation at the right of Fig. 1 but on a much smaller scale;

Fig. 3 is a view, chiefly in elevation, of the apparatus looking toward the right, viewing Fig. 1, principally to illustrate the valve mechanism and the conduits leading thereto and therefrom;

Fig. 4 is a diagram illustrating the relation of the rotary valve ports to the ports of the valve plates when there are an odd number, such as the five illustrated, of textile combing means;

Fig. 5 is a view similar to Fig. 4 when there is an even number, such as four, of the textile combing means;

Fig. 6 is a detail of the means for collecting the noils and short fibres from one of the combing means and a portion of the conduit leading therefrom;

Fig. 7 is a view, chiefly in vertical transverse section, of the rotary valve mechanism and connections;

Fig. 8 is a fragmentary view showing a modified form of the invention.

The apparatus acts selectively to accumulate noils and other short fibres discharged from a plurality of textile combing means.

Such combing means may consist either of one or a plurality of combing machines such, for example, as Noble combs, where it is desired to collect and maintain separate the noils and short fibres discharged from such combing means. In the construction illustrated in the drawings ten combing machines are illustrated arranged in pairs, each pair operating upon a different stock. Since combing machines are well known and familiar it is only necessary to illustrate them diagrammatically. They are illustrated arranged in a straight row but obviously they may be positioned in any desired arrangement as required by the particular mill in which they are located.

The first combing mechanism is made up of a pair of combing machines 1 and 2, the second pair of the machines 3 and 4, the third pair of the machines 5 and 6, the fourth pair of the machines 7 and 8, and the fifth pair of the machines 9 and 10. Each pair of combing machines illustrated discharges the noils and short fibres in the usual manner but instead of dropping on to the floor, or into a can, they are discharged into

a funnel connected to a conduit. In the form illustrated each combing machine, as for example those shown at 1 and 2, discharges at the points 11 and 12, and the discharge at these points in each case is to a funnel such as shown at 13 in Fig. 6, connected to a conduit 14. This conduit conveniently runs along beneath the floor 15, as indicated in Fig. 3, and then rises to the rotary valve mechanism. In a similar way the pair of combing machines 3 and 4 discharge into funnels connected to the conduit 16, also extending beneath the floor and then rising to the rotary valve mechanism. So also the pair of combing machines 5 and 6 discharge into funnels connected to the conduit 17 also extending beneath the floor and then rising to the rotary valve mechanism. In a similar manner the pair of combing machines 7 and 8 discharge through a similar conduit 18, and the pair of combing machines 9 and 10 through the conduit 19.

The receivers for the noils and short fibres discharged from the respective combing means, in the case illustrated the respective pairs of combing machines, may be of any suitable type and need no illustration in detail. Preferred forms of receivers for this purpose are well known and illustrated in my application Serial Number 92,682 filed May 11, 1949, now Patent No. 2,606,344 issued August 12, 1952 and also in application Serial Number 5,554 filed January 31, 1948 now Patent No. 2,505,873 issued May 2, 1950. These receivers are therefore simply illustrated diagrammatically. They correspond in number with the number of combing means working on the same stock and so in the case illustrated there are five receivers, one for each pair of combing machines. These receivers also may be positioned in any suitable position as required by the particular factory in which they are located. The receiver 20 accumulates the discharge from the first pair of combing machines 1 and 2, the receiver 21 accumulates the discharge from the second pair of combing machines 3 and 4, the receiver 22 accumulates the discharge from the third pair of combing machines 5 and 6, the receiver 23 accumulates the discharge from the fourth pair of combing machines 7 and 8, the receiver 24 accumulates the discharge from the fifth pair of combing machines 9 and 10. The conduits 14, 16, 17, 18, and 19, with the interposed rotary valve mechanism respectively connect the respective receivers to the corresponding noil and short fibre collecting means.

Suitable means are provided for exhausting the air from the receivers, or producing a vacuum therein, so as to draw the noils and fibres discharged into the collecting means through the conduits into the receivers and as such air-exhausting means is well known and familiar and is also disclosed in the applications before mentioned, it is only necessary here to illustrate it diagrammatically. At a suitable position there is mounted a vacuum pump 25 driven by an electric motor 26 and producing suction in the conduit 27 having interposed therein a suitable filter receiver 28. This conduit is connected either directly or by branches with each one of the several receivers so as to produce the desired vacuum therein and effect the desired accumulation of the noils and short fibres therein.

The rotary valve mechanism which is located at the point 29, see Fig. 1, in the conduits, is provided with ports which act upon rotation of the valve to establish communication between the re-

spective receivers and the corresponding collecting means in a predetermined sequence to cause the noils and fibres discharged from each textile combing means to be accumulated in the same receiver. A preferred construction of this rotary valve mechanism is shown chiefly in Figs. 3 and 7. This mechanism is preferably supported upon a base 30 carried on columns 31 extending to the floor 15 and is shown as braced by tie rods 32 from the ceiling above. The mechanism comprises a pair of generally similar parallel plates 33 and 34 with a valve member 35 mounted to rotate on a fixed axis between the plates, such as the shaft 36, mounted in the plates. This valve member is provided with a transverse port 37 and preferably, as afterward explained, with two such transverse ports spaced from the axis and opening in close contact with both plates. Each conduit is connected to each of the plates at aligned ports extending transversely through the plates and spaced from the said axis equally with the valve ports and preferably the ports in the valve plates and in the valve are of the same diameter with the ports in each plate spaced apart a distance corresponding to one port. In Fig. 7 the port 37 is shown aligned with the conduit 14 so that in that position suction is maintained from the funnels or collecting means for the combing machines 1 and 2 clear through to the receiver 20, thus causing the noils and short fibres discharged from this pair of combing machines to pass into its corresponding receiver 20.

Suitable means are provided for rotating the valve member to establish communication between the respective receivers and the corresponding collecting means in a predetermined sequence. As one means for that purpose the valve member 35 is provided with a gear 38 on its periphery which may be formed by gear teeth integral therewith and a pinion 39 located between the valve plates and journaled by the shaft 40 in the valve plates cooperates with this gear. The pinion may be driven by any suitable means such as by a gear 41 on the shaft 40 cooperating with a gear 42 on the shaft of a suitable motor 43.

It is desirable to maintain the air-exhausting pressure substantially constant during the operation of the apparatus and this result in the construction illustrated is obtained by providing two ports in the valve member and by spacing the ports in each plate apart a distance corresponding to one port and making the angular relation of the valve ports such as to position one valve port in alignment with one pair of valve plate ports when the other valve port is in alignment with the space between another pair of valve ports. Thus it will be seen that as the valve rotates gradually closing one conduit that another conduit will proportionately and gradually open, thus maintaining substantially constant the air-exhausting pressure. This feature of the invention is illustrated in the diagrams of Figs. 4 and 5. In Fig. 4 the circles 50 represent an arrangement of the valve plate ports when, as in the apparatus illustrated, there is an uneven number, such as five, of the textile combing means. These ports are all equally spaced from the axis 51 and are spaced apart a distance corresponding to one port. The valve member has two ports 52 and the angular relation of these is shown as 180°, or may be any other angular relation which will cause, as illustrated, one of these valve ports 52 when in alignment with one pair of the valve plate ports to position the other valve port 52 covering the space between a pair of valve plate ports.

If there is an even number, such as four, of the alined ports in the valve plates, the same rule applies. In Fig. 5 there is shown an even number, such as four, of the valve plate ports 50 with the space between corresponding to that of one port. Here again the angular relation, in this case 135°, between the two ports 52 of the valve member, is such that when one of these ports is in alinement with valve plate ports the other is in the space between the valve plate ports, thus causing, as the valve rotates, one conduit gradually to close and another proportionately to open, and thus maintain substantially constant the air-exhausting pressure.

Not only is the air exhausted pressure thus maintained substantially constant during the operation of the apparatus, but this result is produced by the employment of a minimum amount of power and this power is exerted in the most efficient manner. The pump has only to maintain the vacuum substantially constant in the entire group of the receivers and from the pump through the rotary valve to but a single intake because as the valve rotates the equivalent of but one intake conduit or pipe is ever connected. Consequently the power required to produce this vacuum operating the entire group of receivers is not greater than that which would be required to produce an equal vacuum in a system extending from the pump through a single receiver to a single intake.

Further, the rotary valve, acting gradually to close and proportionately to open, successive ports, causes a quick and powerful suction to be exerted between the selected receiver and its intake acting quickly to suck the fibre into the receiver.

In the embodiment of the invention above described there is a receiver for each of the plurality of textile combing means. If the plurality of textile combing means are so operating that two of the textile combing means are operating on the same type of fibre stock, it would be within the invention to arrange to have the noils and other short fibres from both of such textile combing means that are operating on the same kind of stock delivered into the same receiver and yet maintain the uniform vacuum pull at the intake funnel of all of the textile combing means. One way of accomplishing this is illustrated in Fig. 8, which is a fragmentary view similar to Fig. 3, showing the valve mechanism with the pipes leading therefrom on the receiver side thereof. In this embodiment one at least of the conduits on the receiver side of the rotary valve is connected by a pipe connection to an adjacent conduit, and valves are suitably installed so that each of the connected conduits can deliver separately into its receiver, or the noils and other short fibres in one of the two connected conduits can be diverted into the other conduit, so that the noils and other short fibres in both conduits will be delivered to the same receiver. For instance, in Fig. 8 the conduits 18a and 17a, which correspond to the conduits 18 and 17 in Fig. 3, are connected by a pipe connection 55 and in which is installed a valve 56. The conduit 18a has a valve 57 therein on the discharge side of the pipe connection 55, and the conduit 17a has a valve 58 therein, also on the discharge side of the connecting pipe 55. With this arrangement if the valve 56 is closed the two conduits 18a and 17a will each deliver to its respective receiver, but if the valve 56 is opened and the valve 57

closed the noils and other short fibres in the conduit 18a will be diverted into the conduit 17a, so that both conduits 18a and 17a will eventually deliver to the same receiver.

- 5 Similarly, if the valve 57 is opened and the valve 58 closed, the valve 56 also being open, the noils and short fibres in the conduit 17a will be diverted into the conduit 18a and will thus be delivered into the corresponding receiver.
- 10 In said Fig. 8 the conduits 19a and 16a are also shown as connected by a pipe connection 59 having a valve 60 therein and the conduit 19a has a valve 61 therein on the discharge side of the pipe connection 59, the conduit 16a also having a similar valve 62 therein on the discharge side of said pipe connection.

20 By manipulating these valves as above described with reference to the valves 56, 57 and 58, the noils and short fibres delivered to the conduit 19a from the rotary valve may be diverted into the conduit 16a, and similarly the noils and short fibres delivered to the conduit 16a may be diverted into the conduit 19a, or by closing the valve 63 and opening the valves 61, 25 62, each conduit 19a and 16a will deliver to its own receiver.

20 There is also shown in Fig. 8 a pipe connection 63 between the conduits 16a and 14a, which conduits correspond to the conduits 16 and 14 in Fig. 3, and the pipe connection 63 has a valve 64 therein, while the conduits 16a and 14a have valves 65 and 66 therein respectively on the discharge side of the pipe connection 63. With the above arrangement the valves may be adjusted 35 so that each conduit will deliver to its particular receiver, or the valves may be arranged so that the noils and short fibres in one conduit may be diverted into another conduit.

30 While the invention has thus been disclosed 40 in connection with selective accumulation of noils and short fibres discharged from a plurality of textile combing machines, it will be understood that in its broader aspects the invention is equally applicable to any apparatus where material at 45 a plurality of stations is transferred selectively therefrom by suction to a plurality of receivers having air-exhausting means connected thereto, thus causing the material at each station to be segregated and accumulated in the same receiver. Such stations are broadly represented or 50 typified by the collecting means described herein.

The invention presents a simple and effective apparatus for the purposes set forth.

Having thus described the invention, what is 55 claimed as new, and desired to be secured by Letters Patent, is:

1. In an apparatus for selectively transferring by suction material, such as noils and short fibres, from a plurality of stations, such as the 60 points of discharge from textile combing means, to a corresponding plurality of receivers having air exhausting means connected therewith and conduits leading from the respective receivers to the corresponding stations, the provision of rotary valve mechanism in said conduits having ports acting upon rotation of the valve gradually to establish communication between one receiver and its corresponding station and proportionately gradually to close communication between another receiver and its corresponding station, thus to maintain substantially constant the air exhausting pressure.

2. In an apparatus having the construction and operation as defined in claim 1, in which the 70 rotary valve mechanism comprises a pair of

parallel plates, a valve member mounted to rotate on a fixed axis between the plates and provided with a transverse port spaced from the axis and opening in close contact with both plates, and in which each conduit is connected to each of said plates at alined ports extending through the plates and spaced from the said axis equally with the valve port.

3. In an apparatus having the construction and operation as defined in claim 1, in which the rotary valve mechanism comprises a pair of parallel plates, a valve member mounted to rotate on a fixed axis between the plates and provided with a transverse port spaced from the axis and opening in close contact with both plates, and in which each conduit is connected to each of said plates at alined ports extending through the plates and spaced from the said axis equally with the valve port, and in which means for rotating the valve are provided comprising a gear on the valve periphery, a pinion between the valve plates journaled in the plates cooperating with the said gear, and means for driving the pinion.

4. In an apparatus having the construction and operation as defined in claim 1, in which the rotary valve mechanism comprises a pair of parallel plates, a valve member mounted to rotate on a fixed axis between the plates and provided with a pair of transverse ports equally spaced from the axis and opening in close contact with both plates, and in which each conduit is connected to each of said plates at alined ports extending transversely through the plates and spaced from the said axis equally with the valve ports and in which the ports in the valve plates and in the valve are of the same diameter with the ports in each plate spaced apart a distance corresponding to one port, and in which the angular relation of the valve ports is such as to po-

sition one valve port in alinement with one pair of valve plate ports when the other valve port is in alinement with the space between another pair of valve plate ports, thus as the valve rotates to cause one conduit gradually to open and another proportionately gradually to close and thus to maintain substantially constant the air-exhausting pressure.

5. In an apparatus having the construction and operation as defined in claim 1, in which the rotary valve mechanism comprises a pair of parallel plates, a valve member mounted to rotate on a fixed axis between the plates and provided with transverse ports equally spaced from the axis and opening in close contact with both plates, in which each conduit is connected to each of said plates at alined ports extending through the plates and spaced from the said axis equally with the valve ports, and in which two of the conduits are connected at a point between the receiver and the valve with shut-off valves in said connection and in each of the connected conduits between the connection and the receiver thus to enable the material, when either of said conduits is opened by the valve, to enter the receiver connected to the other conduit by adjusting said shut-off valves.

ERNEST CLARK.
